CASING PERFORATOR

Aaron English, Bellflower, and Leroy E. Ridgeway,
Compton, Calif.

Application April 5, 1948, Serial No. 18,996

16 Claims. (Cl. 164—0.5)

1

This invention has to do with a casing perforator and it is particularly concerned with a device for perforating casing located in a well and of the type wherein an explosive charge is employed to effect the desired perforating action.

A general object of the present invention is to provide a casing perforator of the type wherein a body carries a barrel so that the barrel is shiftable into close proximity to the casing to be perforated and a charge carried by the barrel is ignited when the barrel reaches the desired position relative to the casing and acts to effect the desired perforation of the casing. With the construction of the present invention the ignition of the charge is effected by means of a shell carried at the forward end of the barrel, which shell is of the rim firing type, the rim of the shell being located to be compressed between the forward end of the barrel and the wall of the casing as the barrel reaches the casing.

Another object of our invention is to provide a well casing perforator of the general character referred to including an improved construction involving a tubular body and barrel guides in the body, which guides are simple tubular parts extending laterally of the body and fixed therein, the structure being such that a single propelling charge located at any desired point in the body will act to effectively propel gun barrels carried in the guides.

A further object of the present invention is to provide a well casing perforator of the general character referred to wherein a gun barrel, operable into close proximity with the casing to be perforated, carries a projectile propelled by an explosive charge carried by the barrel, which projectile is operable through a substantial distance in the barrel after the charge has been ignited, with the result that effective pressure develops behind the projectile before it leaves the barrel to pierce the casing.

A further object of the present invention is to provide a well casing perforator with a gun barrel of the general character referred to wherein an actuating shell is carried in the nose of the barrel, ignited by contact with the casing and serving to drive a shell rearward in the barrel to strike a firing pin at the rear of the barrel in such manner as to actuate a cap which ignites the propelling charge that then drives the projectile forward in the barrel to pierce the casing.

The various objects and features of our invention will be fully understood from the following detailed description of typical preferred forms and applications of the invention, throughout

2

which description reference is made to the accompanying drawings, in which:

Fig. 1 is a vertical sectional view of a typical well showing a casing therein and an unactuated perforator embodying the present invention located within the casing. Fig. 2 is a sectional view similar to a portion of Fig. 1 showing the perforator actuated. Fig. 3 is an enlarged sectional view of a portion of the structure shown in Figs. 1 and 2, being an enlarged view taken as indicated by line 3—3 on Fig. 1. Fig. 4 is a transverse or plan section taken as indicated by line 4—4 on Fig. 3. Fig. 5 is an enlarged detailed sectional view taken as indicated by line 5—5 on Fig. 4. Fig. 6 is a perspective view of a shell employed for effecting operation of the explosive charge and Fig. 7 is a detailed sectional view of a modified form of construction showing the nose portion of a gun barrel carrying an explosive charge in such manner that the charge itself effects perforation of the casing without utilizing a projectile for that purpose.

The structure provided by the present invention is useful generally where it is desired to provide perforations, or the like, in inaccessible objects, as for instance casings located in wells or other such situations. For example, we will describe the present invention as applied to a well casing in which situation it is employed to effect a plurality of perforations at suitable spaced intervals in the casing. In the particular case illustrated a well casing A is shown situated in a well bore W and the perforator embodying the present invention is shown carried by an operating member or line C carrying an electric control member or wire X.

The perforator embodying the present invention includes, generally, an elongate tubular body B, a gun barrel D, a mounting E for the gun barrel supporting it to shift into engagement or close proximity to the casing A, operating means F for the gun barrel acting to shift it in the mounting E, an explosive charge G carried by the barrel operable to effect penetration of the casing, and means H for igniting the charge G.

In the form of the invention illustrated in Figs. 1 to 6, inclusive, the structure involves a projectile J slidably carried in the gun barrel, a driver K carried in the barrel behind the projectile, a percussion cap L carried by the driver and a firing pin M at the charge G. The last named elements are so related that when the means H is actuated, as by contact with the casing A, the projectile J with the driver K behind it is driven rearwardly in the gun barrel, mov-

ing the cap L into contact with the firing pin M so that the charge G is ignited to thereupon drive or force the driver and projectile forward in the barrel in such manner as to have substantial velocity when the projectile reaches the casing.

The body B of the perforator is an elongate tubular structure, preferably carrying a plurality of units each involving a gun barrel D, a mounting E for the barrel, and various other elements combined therewith as herein described. It is ordinarily desirable to perforate a casing at a plurality of points spaced circumferentially of the casing and also longitudinally thereof. In the drawings we have shown a body B carrying a plurality of gun barrels in such manner as to perforate a casing in the manner just mentioned simultaneously, or in a single operation.

The particular body B is shown as involving a shell 10 which may be in the form of a length of tubing, or the like, a head 12 closing the upper end of the shell 10, and a plug 13 closing the lower end of the shell. The shell of the body serves to support the several perforating units as will be hereinafter described, that is, it supports the several mountings which, in turn, carry the gun barrels while the head 12 serves as an element to carry the operating means F and as an element connecting the perforator with the operating line C. The line C is shown connected with the head 12 through a suitable coupling 14 and a socket 15 in the inner end of the head open to the shell 10 carries the means F.

The plug 13 closing the lower end of the shell 10 is preferably provided with a controlled vent opening 16 so that after the means F has operated pressure is allowed to bleed from the body. In the particular case illustrated the vent opening 16 is shown controlled by a bane or orifice member 17 having an aperture or orifice of such size as to allow pressure to gradually bleed from the body after initial operation of means F has generated sufficient pressure to fully and properly operate the several gun barrels carried by the structure.

The operating means or member C may be of any desired form or construction so long as it is such as to handle the body B enabling it to be run into the casing A to the desired point. In practice it is advantageous to employ a cable or flexible line to handle the body B and in the case illustrated we have shown an operating means F involving an electrically actuated igniter 20 and, therefore, have shown the cable or line C as including an electric operating line or wire X.

In carrying out the present invention the several perforating units carried by the body B may be alike and, therefore, one such unit will be described, it being understood that such description may apply to all of the units involved in the structure.

The guide means E provided to carry a gun barrel may be fixed in or to the body 10 and is such as to slidably support a gun barrel D. In the preferred construction the means E involves an elongate tubular part 21 with a guideway or guide opening 22 and the tubular part is supported by or fixed in the shell 10 of the body. The guide E may be positioned or disposed in any suitable manner, it being preferred, however, that it be arranged to extend laterally of the body B with its opening 22 extending radially and opening at one side of the body to face the inner wall of casing A.

In practice the guide member 21 may be varied widely in form and construction and in

the manner in which it is mounted in the shell of the body. In the case illustrated the member 21 is a simple elongate tubular part open at both ends and it has its forward or outer end engaged in an opening 23 in the shell 10 of the body where the guide is fixed to the body as by welding 24, or the like. The inner end 25 of the guide member 21 may terminate short of the wall of the shell diametrically opposite the opening 23. In the case illustrated the inner end 25 of the guide 21 is flat or normal to the longitudinal axis of the guide and the points or parts of the guide which closely approach the inner wall of the shell are secured thereto as by welding 26. Through the construction just described the guide member 21 is effectively supported at both ends, the outer end of the guide being open toward the inner wall of casing A, while the inner end of the guide is open to the interior of the shell 10.

The gun barrel D is slidably carried by the means E to be shiftable from a retracted position such as is shown in Fig. 3 to an operated or extended position such as is shown in Fig. 2, where its outer or forward end is in close proximity to, or in engagement with, the inner wall of casing A. The barrel D is provided primarily as a carrier for the explosive charge G which, when ignited serves to effect perforating of the casing A and incidental to this basic function it carries the means H and when parts such as the projectile and driver are used it carries these parts also.

In the form of the invention illustrated the barrel D is shown as an elongate element corresponding in cross section with the guide opening 22 in guide member 21. The guide opening or bore 22 in member 21 is shown as round in cross section and, therefore, the exterior 30 of the gun barrel D is turned or round in cross section and is slidably fitted in the bore 22. The barrel is of such length that when in an in or retracted position its rear end is opposite or at the rear end 25 of the guide member 21 while its forward end or nose 31 is within the forward end portion of the guide 21 as shown in Fig. 3. In the preferred construction the forward end portion or nose 31 of the gun barrel is rounded so that when the barrel is operated or moved to an out position the means H carried by the barrel, preferably centrally thereof, is moved into contact with the casing, without interference from the nose portion of the barrel.

The gun barrel D is provided with a bore 35 that receives or holds the means H and with a charge opening or chamber 36 that carries the explosive charge G. In the preferred arrangement the bore 35 and chamber 36 are centrally located in the barrel or are concentric with the longitudinal axis of the barrel and they are in communication with each other, the chamber 36 being in communication with the inner or rear end of the bore 35 while the forward end of the bore 35 is such as to receive and hold the means H.

In the form of the invention under consideration, that is, where a projectile J and drive K are employed, the bore 35 is of substantial length, the charge opening 36 being located in and confined to the rear end portion of the gun barrel so that the bore 35 extends substantially the entire length of the gun barrel and supports the projectile J and driver K so that they are free to move a substantial distance in the barrel from

a forward position adjacent the means H to a rear position where they are at the chamber 36.

The gun barrel 35 as above described is open at both ends, that is, its forward end is open toward or at the nose of the gun barrel so that it faces the wall of the casing, while the rear end of the bore is open and in communication with the chamber 36. The chamber 36 is in the nature of an enlargement or cavity in the rear end portion of the gun barrel and its rear end is closed by a closure or plug 40 which is preferably removable, being in the nature of a threaded plug having screw threaded engagement with the rear end portion of the gun barrel.

The operating means F carried by body B is a pressure means preferably involving a pressure generating charge 41 carried in the socket or opening 15 provided in the head 12 of the body B. The charge 41 may be a body of suitable powder and in the case illustrated it is such as to be ignited by an electrically actuated igniter 20 which is imbedded in the charge. The igniter 20 is shown suitably connected with the operating line or wire X so that when it is desired to actuate the perforator the line X is energized, causing the igniter 20 to operate, which in turn ignites charge 41.

When the charge 41 is ignited a substantial pressure generates in the body B, in fact, enough pressure is developed in the body so that the several barrels D carried thereby are propelled or driven forward or outward in their mountings E, bringing the nose portions into engagement with or into close proximity with the inner wall of casing A. The charge 41 is such as to propel the barrels D forward with sufficient pressure to insure proper operation of the means H carried by the gun barrels for igniting the charges G.

The charge G carried by gun barrel D is preferably a powerful or high explosive such for example as a body of black pistol powder, or the like. In the preferred form of the invention the charge G is in the form of a cake or block of the desired powder and is fashioned to occupy the charge chamber 36 in a manner such as is clearly illustrated in Fig. 4 of the drawings. With the construction above described the plug 40 is removed to allow for introduction of the charge G into the chamber 36 and when the plug 40 has been reapplied or arranged in place the charge chamber is closed, confining the charge G in the chamber so that when the charge is ignited the pressure generated thereby can escape only through the bore 35 of the gun barrel.

The means H provided for igniting the explosive charge G involves primarily a percussion cap or shell 50 carried in the forward end portion of the gun barrel 35. In accordance with the preferred form of the invention the shell 50 is of the rim-firing type and has a case 51 slidably fitted into the forward end portion of barrel 35 and has a head 52 on the outer end of the case. The head projects somewhat radially from the case to overlie the end of the gun barrel beyond the bore. The rim portion of the head is such as to carry a percussion charge ignited when the gun barrel is forced forward causing the rim of the head to be put under pressure between the nose of the barrel and the wall of the casing. A suitable powder charge in the case 51 is ignited by the head developing pressure which effects ignition of the charge G.

In the form of the invention under consideration the operation of means H indirectly effects ignition of charge G. In this case the means

H acts to drive or propel the projectile J rearwardly in the barrel 35 from a forward or initial position in the forward end portion of the barrel. As the projectile J is initially located in the barrel it is adjacent the means H and the driver K is preferably adjacent the rear end of the projectile and is consequently in a forward position. The percussion cap L is carried by the rear end of the driver being carried in a socket 55 in the driver.

When the means H is actuated the charge carried thereby develops sufficient pressure to drive or thrust the projectile J and driver K rearwardly in the barrel in such manner as to move the cap L into operating engagement with the firing pin M. The firing pin M is shown as carried by the plug or closure 40 in such manner as to extend through the charge G and has an exposed tip facing the rear end of the bore 35.

When the driver K reaches the firing pin as a result of actuation by means H, the firing pin engages the percussion cap L in the driver so that the cap is ignited. When the cap is thus ignited it is immediately adjacent or in contact with the charge G and consequently causes ignition of the charge G. Upon ignition of charge G a high pressure is rapidly developed in the charge chamber 36 which can escape only through the barrel 35 and as a result the driver K, which is preferably a slug of lead, or the like, acts behind the projectile J as a ram in the bore 35 forcing the projectile J forward in the bore and into engagement with the casing A to pierce the casing and pass completely through it.

In practice the projectile J may be of any suitable form or type, it being preferred ordinarily to employ a projectile with a pointed nose 60 such as to effectively penetrate the casing A. In accordance with the preferred form or construction the projectile is a substantial distance inward of the forward end of the barrel 35 when the driver moves the cap L into operating engagement with the firing pin M, with the result that the projectile moves a substantial distance forward within the barrel 35 before reaching the casing, so that a substantial pressure is developed by the charge G in the barrel 35 behind the projectile, effectively driving the projectile through the casing as the projectile reaches the casing to penetrate it.

In the form of the invention illustrated in Fig. 7 of the drawings the projectile J, driver K, percussion cap L and firing pin M are eliminated and the explosive charge G instead of being located at the rear of the gun barrel is located in a charge chamber 36^a at the forward end portion or nose portion of the gun barrel. The gun barrel in this case has a removable tip or nose end 70 which confines the charge G' in the charge chamber 36^a and the bore 35^a of the gun barrel is formed in or through the tip end 70. The bore 35^a is such as to carry the means H' which, as in the case above described, involves a shell 50^a of the rim firing type.

With the arrangement just described when the shell 50^a is ignited by contact of its rim with the casing A or between the nose of the barrel and the casing A, the charge in the shell immediately and directly ignites the explosive charge G' and the force generated by ignition of the charge G' is confined and directed by the barrel 35^a onto or at the wall of casing A in such manner that the charge directly penetrates the casing making a projectile unnecessary.

In the form of the invention shown in Fig. 7 the explosive charge G' may be dynamite or other high explosive such as will generate a force or pressure effective in penetrating the casing without utilizing a projectile.

Having described only typical preferred forms and applications of our invention, we do not wish to be limited or restricted to the specific details herein set forth, but wish to reserve to ourselves any variations or modifications that may appear to those skilled in the art and fall within the scope of the following claims:

Having described our invention, we claim:

1. A casing perforator including, a body insertable into the casing, an elongate barrel with a chamber therein open at the forward end of the barrel, means mounting the barrel in the body to shift laterally of the casing from a retracted position spaced a substantial distance from the wall of the casing to an extended position where the forward end of the barrel is immediately adjacent the wall of the casing, a charge carried by the barrel and generating force delivered through the opening at the forward end of the body to effect penetration of the casing, and means for igniting the charge including an explosive shell carried by the muzzle portion of the barrel and having an igniting head seated on the forward end of the barrel to be actuated by compression between the end of the barrel and the wall of the casing when the barrel is moved to the extended position.

2. A casing perforator including, a body insertable into the casing, an elongate barrel with a chamber therein open at the forward end of the barrel, means mounting the barrel in the body to shift from a retracted position spaced a substantial distance from the wall of the casing to an extended position where the forward end of the barrel is immediately adjacent the wall of the casing, means carried by the body adapted to operate the barrel to the extended position, a charge carried by the barrel and generating force delivered through the opening at the forward end of the body to effect penetration of the casing, and means for igniting the charge including a rim fired explosive shell carried by the muzzle portion of the barrel and having an igniting head with its rim seated on the forward end of the barrel to be actuated by compression between the end of the barrel and the wall of the casing when the barrel is moved to the extended position.

3. A casing perforator including, a body insertable into the casing, an elongate barrel with a chamber therein open at the forward end of the barrel, means mounting the barrel in the body to shift from a retracted position spaced a substantial distance from the wall of the casing to an extended position immediately adjacent the wall of the casing including a tubular guide and means fixing the guide to the body with an open end of the guide facing the wall of the casing, a charge carried by the barrel and generating force delivered through the opening at the forward end of the body to effect penetration of the casing, and means for igniting the charge including an explosive shell carried by the muzzle portion of the barrel and having an igniting head seated on the forward end of the barrel to be actuated by compression between the end of the barrel and the wall of the casing when the barrel is moved to the extended position.

4. A casing perforator including, an elongate tubular body insertable into the casing, an elon-

gate barrel with a chamber therein open at the forward end of the barrel, means mounting the barrel in the body to shift from a retracted position spaced a substantial distance from the wall of the casing to an extended position immediately adjacent the wall of the casing including, a tubular guide extending transversely of the body and means fixing the guide in the body with an open end of the guide facing the wall of the casing, a charge carried by the barrel and generating force through the opening at the forward end of the body to effect penetration of the casing, and means for igniting the charge including an explosive shell carried by the muzzle portion of the barrel and having an igniting head seated on the forward end of the barrel to be actuated by compression between the end of the barrel and the wall of the casing when the barrel is moved to the extended position.

5. A casing perforator including, an elongate tubular body insertable into the casing, an elongate barrel with a chamber therein open at the forward end of the barrel, means mounting the barrel in the body to shift transversely thereof from a retracted position spaced a substantial distance from the wall of the casing to an extended position immediately adjacent the wall of the casing including a tubular guide extending transversely of the body and supported thereby with an open end facing the wall of the casing, a charge carried by the barrel, and means for igniting the charge carried by the muzzle portion of the barrel and adapted to engage the casing.

6. A casing perforator including, a tubular body insertable into the casing, an elongate barrel with a charge carrying chamber therein open at the forward end of the barrel, means mounting the barrel in the body to shift from a retracted position spaced a substantial distance from the wall of the casing to an extended position immediately adjacent the wall of the casing including a tubular guide extending transversely of the body and supported thereby with an open end facing the wall of the casing, means carried by the body operating to shift the barrel to the extended position, a charge carried by the barrel, and means for igniting the charge carried by the muzzle portion of the barrel and adapted to engage the casing.

7. A casing perforator including, a tubular body insertable into the casing, an elongate barrel with a charge carrying chamber therein open at the forward end of the barrel, and means mounting the barrel in the body to shift from a retracted position spaced a substantial distance from the wall of the casing to an extended position immediately adjacent the wall of the casing including a tubular guide extending transversely of the body and having its forward end fixed to the body and open toward the casing, a charge carried by the barrel, and means for igniting the charge carried by the muzzle portion of the barrel and adapted to engage the casing.

8. A casing perforator including, a tubular body insertable into the casing, an elongate barrel with a charge carrying chamber therein open at the forward end of the barrel, means mounting the barrel in the body to shift from a retracted position to an extended position immediately adjacent the wall of the casing including a tubular guide extending transversely of the body with its ends fixed to the body, the forward

end of the guide being open to the casing and the other end of the guide being open to the interior of the body and supported thereby with an open end facing the wall of the casing, means carried by the body operating to shift the barrel, a charge carried by the barrel, and means for igniting the charge carried by the muzzle portion of the barrel and adapted to engage the casing.

9. A casing perforator including, an elongate tubular body insertable into the casing, an elongate barrel with a charge carrying chamber therein open at the forward end of the barrel, a guide slidably supporting the barrel extending transversely of the body and having its outer end opening toward the wall of the casing and having its inner end in communication with the interior of the body, and means carried by the body generating pressure in the body to enter the guide and operate the barrel therein, a charge carried by the barrel, and means for igniting the charge carried by the muzzle portion of the barrel and adapted to engage the casing.

10. A casing perforator including, an elongate tubular body insertable into the casing and including an elongate tubular shell, a plug closing the lower end of the shell and a head closing the upper end of the shell, a barrel, a guide slidably supporting the barrel, means supporting the guide in the body with the guide extending transversely of the body and having its outer end opening toward the wall of the casing and having its inner end in communication with the interior of the body, and means carried by the head of the body generating pressure in the body to enter the guide and operate the barrel therein, the guide having its outer end fixed to the shell of the body, a charge carried by the barrel, and means for igniting the charge carried by the muzzle portion of the barrel and adapted to engage the casing.

11. A casing perforator including, an elongate tubular body insertable into the casing, a plurality of elongate barrels each with a charge chamber open at the forward end of the barrel, guides slidably supporting the barrels, the guides being tubular elements spaced axially of the body and extending transversely of the body with their outer ends opening toward the wall of the casing, and means carried by the body generating pressure in the body to operate the barrels outwardly in the guides, a charge carried by the barrel, and means for igniting the charge carried by the muzzle portion of the barrel and adapted to engage the casing.

12. A casing perforator including, an elongate body insertable in the casing, a barrel carried by the body and operable relative thereto in a direction transversely thereof to a position immediately adjacent the casing and having a charge chamber therein opening toward the casing, means shifting the barrel relative to the body, an explosive charge in the chamber, and means operating to ignite the charge and including an explosive shell carried by the barrel at the muzzle portion thereof and adapted to engage the casing, the barrel having a jet opening directed toward the casing and directing the force of the ignited charge at the casing to penetrate it.

13. A casing perforator including, a body insertable into the casing, an elongate barrel hav-

ing a chamber therein and including a detachable head at the forward end of the barrel and closing the chamber, the head having a jet opening therein extending longitudinally of the barrel and in connection with the chamber, an explosive charge in the chamber and confined thereto by the head, means mounting the barrel in the body to shift laterally of the casing from a retracted position where the head is spaced a substantial distance from the wall of the casing to an extended position where the head is immediately adjacent the wall of the casing, means adapted to shift the barrel from the retracted to the extended position, and means adapted to ignite the charge including an explosive shell carried by the head and adapted to engage the wall of the casing upon the barrel being operated to the extended position.

14. A casing perforator including, a body insertable into the casing, a barrel slidably carried by the body and operable relative thereto to a position immediately adjacent the casing and having a bore and a charge chamber at the rear end of the bore, means shifting the barrel relative to the body, a projectile operable in the bore, an explosive charge in the chamber, and an explosive shell carried in the forward end portion of the bore with an igniting head engageable with the casing, the shell being adapted to propel the projectile rearwardly in the bore to effect ignition of the charge so the projectile is propelled from the forward end of the barrel by the charge.

15. A casing perforator including, a body insertable into the casing, a barrel slidably carried by the body and operable relative thereto to a position immediately adjacent the casing and having a bore and a charge chamber at the rear end of the bore, means shifting the barrel relative to the body, a projectile operable in the bore, an explosive charge in the chamber, a percussion cap to ignite the charge, and a shell carried by the forward end portion of the barrel and adapted to propel the projectile rearwardly in the barrel to ignite the cap.

16. A casing perforator including, a barrel operable to a position immediately adjacent the casing and having a bore and a charge chamber at the rear end of the bore, a projectile operable in the bore, an explosive charge in the chamber, a firing pin at the charge, a driver in the bore behind the projectile, a percussion cap carried by the driver to be ignited by the pin, and an explosive shell carried in the forward end portion of the bore and having an igniting head engageable with the casing.
